COMBINATION HOLDER AND FLEXIBLE HANDLE FOR CONTAINERS

Earl S. Tupper, Smithfield, R.I., assignor to Tupper Corporation, North Smithfield, R.I., a corporation of Delaware

Application May 21, 1958, Serial No. 51,000

Term of patent 14 years

(Cl. D58—26)

Figure 1 is a view in perspective of a combination holder and flexible handle for containers, embodying my new design;

The broken line showing on the drawing is for illustrative purposes only.

I claim:

The ornamental design for a combination holder and flexible handle for containers, substantially as shown and described.
